UNITED STATES PATENT OFFICE.

OLE O. STORLE, OF TACOMA, WASHINGTON.

AUTOMATIC STOP FOR GRAMOPHONES.

1,423,044.

Specification of Letters Patent.

Patented July 18, 1922.

Application filed April 30, 1920. Serial No. 377,931.

To all whom it may concern:

Be it known that I, OLE O. STORLE, a citizen of the United States, residing at Tacoma, in the county of Pierce and State of Washington, have invented certain new and useful Improvements in Automatic Stops for Gramophones, of which the following is a specification, reference being had to the accompanying drawing, forming a part 10 thereof.

The main objects of this invention are to automatically stop such machines upon the completion of the reproduction of records of different lengths without the necessity of 15 adjusting the stop mechanism for each record; and generally to simplify and improve the construction and operation of stops of this class.

It consists in the construction, arrangement and combination of parts as herein-after particularly described and pointed out in the claims.

In the accompanying drawing like characters designate the same parts in the several figures.

Figure 1 is a plan view of an automatic stop embodying the invention as applied to a gramophone, parts of which are shown; Fig. 2 is a vertical section on the line 2—2, 30 Fig. 1; and Fig. 3 is a plan view similar to Fig. 1, showing the brake applied, and the brake releasing mechanism in a different condition from that shown in Fig. 1.

In the drawing 1 designates the top board 35 or plate of a gramophone case, to the under side of which the motor (not shown) is usually fastened, 2 the turn table, 3 the rotary spindle on the upper end of which the turn table is removably mounted, 4 a record disk 40 shown in Fig. 2 in position for reproduction, 5 the tone or stylus arm carrying the sound box 6 and needle or stylus 7, all of which are or may be of the usual construction, arrangement and mode of operation.

45 The stop comprises a brake and brake releasing mechanism. The brake is mounted on a plate 9, which is fastened in proper position to the top board 1 underneath the turn table.

50 The brake controlling and releasing mechanism is mounted on a plate 11, which is fastened to the under side of the top board 1 below an opening therein.

The brake consists of a lever 13, pivotally 55 mounted or fulcrumed on the plate 9 and

provided with a shoe or pad 14 of leather or other suitable material for engagement with the depending rim of the turn table 2. One arm 15 of the brake lever, which is of angular or elbow shape, projects outwardly 60 between the top board 1 and rim of the turn table, and serves as a handle for manual operation of the brake.

The plate 9 is formed or provided with an upwardly projecting lug 16, which serves 65 as a stop, by engagement with the handle arm 15 of the brake lever, to limit the movement of the brake shoe or pad 14 away from the rim of the turn table, as shown in Fig. 1. A spring 17, connected at one end by a 70 link 18 with the brake lever 13, and at the other end with a stud 19 projecting upwardly from the plate 9, tends to hold the brake in its off position, as shown in Fig. 1, and when it is partially turned from that 75 position, to instantly carry the shoe or pad 14 into engagement with the rim of the turn table, thereby applying the brake and stopping the machine.

The brake releasing mechanism comprises 80 a rotary trip, which as shown, consists of a stud 21 projecting upwardly from a gear 22 journaled on a stud 23 on the plate 11 and meshing with a pinion 24 on the spindle 3.

The plate 11 is formed or provided with a 85 box or bearing 26, fitting the spindle 3 below the pinion 24, and thus determining the position of the gear 22 to properly mesh with the pinion. The box or bearing 26 may, as shown in Fig. 2, extend downwardly 90 and fit into an opening in the top of the motor case or frame 27.

A horizontally swinging arm or supporting member 29 is pivotally mounted on a stud 30, fastened to and projecting upwardly 95 from the plate 11, and extends therefrom inwardly towards the gear 22. It is formed or provided at its free end with a curved wiper arm 31, extending over the gear 22 normally into the path of the trip stud 21. 100 It is also formed or provided further from the center of the gear 22, generally opposite but in a higher plane than the arm 31, with a stop arm 32, which is curved at its free end inwardly towards the gear. An adjustable stop screw 34, threaded in a bracket 35 fastened to the plate 11, is arranged to limit the movement of the arm or support 29, and with it, the movement of the wiper arm 31 towards the path of the trip or stud 21. A 110

spring 36 tends to hold the arm or support 29 against the stop screw 34. A lever having three arms, 38, 39 and 40, is fulcrumed or pivotally mounted on and carried by the 5 arm or support 29. The arm 39 extends over the gear 22 normally into the path of the trip or stud 21, as shown in Fig. 1. A thrust bar or brake releasing member 42, is pivotally connected at one end with the brake 10 lever 13 and extends inwardly therefrom over the stop arm 32, on which it loosely rests and from which it extends inwardly and downwardly over the gear 22. Adjacent its inner end it is formed with an offset 15 shoulder 43, which is movable into and out of the path of the trip stud 21. The bar 42 is connected by a link 44 with the long lever arm 38, and is provided with a pin 45 which projects downwardly therefrom between the 20 arms 31 and 32, which limit the movements of the inner shouldered end of the bar towards and from the center of the gear 22.

A friction segment or wiper 47 is fastened to the tone arm 5 and movable there- 25 with over the turn table 2, into and out of position to engage with the short lever arm 40, the working edge or face of the segment or wiper adjacent the end which first engages with the lever arm 40 as the tone arm 30 swings inwardly over the turn table, being more sharply curved or inclined towards the axis on which the tone arm swings.

In the operation of the stop the brake being applied as shown in Fig. 3, a record 35 placed on the turn table as shown in Fig. 2, and the tone arm 5 swung into position to enter the stylus 7 in the outer turn of the record groove, the segment or wiper 47 is withdrawn from contact with the lever arm 40, and the arm or support 29 is held by the 40 spring 36 against the stop screw 34.

The brake being thrown by the handle 15 into its off position as shown in Fig. 1, and as indicated by dotted lines in Fig. 3, 45 the turn table with the record thereon is rotated as indicated by an arrow on Fig. 1, and the tone arm 5 with the segment or wiper 47, is slowly swung inwardly over the record.

50 With the rotation of the record and turn table, the gear 22 is turned at a slower speed in a reverse direction, as indicated by an arrow on Fig. 1, the trip stud describing a circular path as indicated by a dotted circle 55 on Figs. 1 and 3.

While the arm or support 29 is held against the stop screw 34 by the spring 36, the stop arm 32 engaging with the pin 45, holds the shoulder 43 at the inner end of the 60 bar 42 inwardly out of the path of the trip stud 21 as the stud passes the shoulder and throughout the greater part of its circuit. After passing the shoulder 43 the stud by engagement with the wiper arm 31, turns said arm with the arm 29 and the lever 65

mounted thereon, momentarily away from the center of the gear and from the stop screw with each revolution of the gear, thereby shifting the shoulder 43 into the path of the trip stud. As soon however, as 70 the trip stud clears the arms 31 and 39, the arm or support 29 is shifted back to its former position against the stop screw 34, thereby carrying the shoulder 43 inwardly out of the path of the trip stud. 75

As the stylus 7 approaches the end of the record groove, the segment or wiper 47 is brought into engagement with the lever arm 40, thereby swinging the arm or support 29 into and holding it in the position in which 80 it is shown in Fig. 1. The segment or wiper 47 engaging with the lever arm 40, turns the lever arm 38 inward, and through the link 44 shifts the inner end of the thrust bar 42 with the shoulder 43 inwardly out of the 85 path of the trip stud 21, as shown in Fig. 1. With each revolution of the gear 22 the trip stud 21, after passing the shoulder 43, engages with the lever arm 39, and turns it with the arm 38 and the thrust bar 42 out- 90 ward, as indicated by dotted lines in Fig. 1. The shoulder 43 is thus shifted temporarily into the path of the trip stud 21 with each revolution of the gear, but as this occurs after the trip stud has passed the shoulder 95 43, it will have no effect on the brake.

When the stylus reaches the end of the record groove and the inward movement of the tone arm 5 with the segment or wiper 47 is arrested, the inner end of the thrust bar 42 with the shoulder 43 will be left in the path of the trip stud 21, and on the next revolution of the gear 22, will engage with the shoulder and push the thrust bar length- 100 wise outward, thereby turning the arm of the brake lever 13 which carries the pad or shoe 14 outward till the pivot connection between the link 18 and the handle arm 15 of the lever is shifted inwardly beyond a straight line passing through the fulcrum of the lever and the stud 19. The spring 17 then instantly throws the shoe or pad 14 into engagement with the rim of the turn table, 105 and stops the machine. This action of the 110 spring in applying the brake and shifting the thrust bar 42 outward, carries the pin 45 into contact with the curved arm 32, and thereby shifts the shoulder 43 at the inner end of the thrust bar inwardly out of the path of the trip stud 21, as indicated by dotted lines in Fig. 3, and permits the trip 115 stud to pass into engagement with the wiper arm 31, as shown by full lines in Fig. 3.

The engagement of the trip stud with the arm 31 as the brake is applied and the machine is stopped, shifts the arm or support 29 out of engagement with the stop screw 34 and carries the short lever arm 40 out of engagement with the segment or wiper 47, thus leaving the segment or wiper to be swung 120 125 130

with the tone arm 5 outwardly into position for replacing or repeating a record, without dragging on the arm 40.

Various changes in minor details of construction and arrangement of parts may be made without departure from the principle and scope of the invention as defined in the following claims.

I claim:

- 10 1. In an automatic stop for gramophones the combination with a brake and means for releasably holding the brake in off position, of a trip adapted to be rotated by the rotation of the turn table, a brake releasing member movable into and out of the path of the trip, a pivoted support adapted in normal position to hold the releasing member in inoperative position, a lever carried by said support and connected with the releasing member, and a member movable with the tone arm of the gramophone and tending by engagement with said lever to shift the releasing member out of operative position as the tone arm swings inwardly over a record, the trip being adapted by engagement with said lever to periodically shift the releasing arm into operative position while the turn table rotates.
- 20 2. In an automatic stop for gramophones the combination with a brake and means for releasably holding the brake in off position, of a trip adapted to be rotated by the rotation of the turn table, a brake releasing member movable into and out of the path of the trip, a pivoted support adapted in its normal position to prevent engagement of the releasing member with the trip, means tending to shift said support into and to hold it in its normal position, a lever carried by said arm and connected with the releasing member, and a wiper adapted to be connected and to move with the tone arm and tending by engagement with said lever to shift the releasing member away from the path of the trip as the tone arm swings inwardly over a record, the trip being adapted on each revolution thereof to engage with said lever and shift the releasing member into the path of the trip, and after actuating the releasing member to engage with the lever supporting arm and shift the lever therewith and hold it out of engagement with the wiper.
- 30 3. In an automatic stop for gramophones, the combination with a brake and means for releasably holding the brake in off position, of a pinion on the turn table spindle, a gear meshing with the pinion and provided on one side with a trip stud, a thrust bar pivoted at one end to the brake and movable
- 35 at the other end into and out of the path of the stud, a pivoted support yieldingly held in normal position in which it holds the thrust bar out of the path of the stud, a lever carried by said support and connected by a link with the thrust bar, and a wiper connected and movable with the tone arm and adapted by engagement with said lever as the tone arm swings inwardly over a record, to shift and hold said support out of its normal position and to shift the thrust bar out of the path of the stud, the stud on said gear being arranged to engage with the lever and shift the thrust bar into the path of the stud with each revolution of the gear.
- 40 4. In an automatic stop for gramophones, the combination of a brake lever, a spring connected therewith and adapted to hold the brake in off position and to apply it when it is partially shifted from that position, a trip adapted to be rotated with the rotation of the turn table, a thrust bar pivoted at one end to the brake lever and movable at the other end into and out of the path of the trip, a pivoted support adapted in normal position to hold the thrust bar out of the path of the trip, a stop for limiting the movement of said support towards the path of the trip, a spring tending to hold said support against said stop, a lever carried by said support and connected with the thrust bar, and a wiper connected and movable with the tone arm and tending by engagement with said lever to shift the thrust bar out of the path of the trip as the tone arm swings inwardly over the turn table, the trip being adapted on each revolution thereof after it has cleared the thrust bar to shift the same back into the path of the trip, and when the inward movement of the tone arm is arrested and the thrust bar is left in the path of the trip, to engage with and actuate the thrust bar and partially shift the brake from its off position till the spring becomes effective to apply it.
- 45 5. In an automatic stop for gramophones, the combination with a brake and means for releasably holding the brake in off position and applying it when released, of brake releasing mechanism comprising a pinion on the turn table spindle, a gear meshing with the pinion and a stationary plate on which the gear is mounted having a bearing fitting the spindle and determining the proper relation of the gear to the pinion.
- 50 In witness whereof I hereto affix my signature.
- 55

OLE O. STORLE.
